GAS LASER

Robert C. Rempel, Los Altos, Leslie L. Morris, Milpitas,
and Charles E. Jones, Sunnyvale, Calif., assignors to
Spectra-Physics, Inc., Mountain View, Calif., a corpo-
ration of California

Filed Aug. 14, 1963, Ser. No. 76,207

Term of patent 14 years

(Cl. D26—14)

Des. 199,442

PAGE 2

FIGURE 1 is a top perspective view of gas laser embodying our design;

FIGURE 2 is a side elevational view of the laser of FIGURE 1, the two sides being substantially identical in appearance;

FIGURE 3 is a right end view of the laser of FIGURE 1;

FIGURE 4 is a left end view of the laser of FIGURE 1; and

FIGURE 5 is a bottom perspective view of the laser of FIGURE 1.

The dominant features of our new design are shown in solid lines in the drawing.

We claim:

The ornamental design for a gas laser, as shown and described.
